(57) **CLAIM**

The ornamental design for a payment device, as shown.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment the invention showing my design;

FIG. 2 is a front elevation view of the embodiment of FIG. 1;

FIG. 3 is a rear elevation view of the embodiment of FIG. 1;

FIG. 4 is a top elevation view of the embodiment of FIG. 1;

FIG. 5 is a right side elevation view of the embodiment of FIG. 1; and,

FIG. 6 is a left side elevation view of the embodiment of FIG. 1.

1 Claim, 6 Drawing Sheets
(2 of 6 Drawing Sheet(s) Filed in Color)
